Geo. R. Blodgett,

Attn.

UNITED STATES PATENT OFFICE.

WILLIAM B. POTTER, OF SCHENECTADY, NEW YORK, ASSIGNOR TO THE THOMSON - HOUSTON ELECTRIC COMPANY, OF BOSTON, MASSACHUSETTS.

DESIGN FOR AN INSULATING-CHUTE.

SPECIFICATION forming part of Design No. 23,951, dated January 8, 1895.

Application filed November 19, 1894. Serial No. 529,345. Term of patent 14 years.

To all whom it may concern:

Be it known that I, WILLIAM B. POTTER, a citizen of the United States, residing at Schenectady, in the county of Schenectady, State of New York, have devised and invented a new and useful Design for Insulating-Chutes, of which the following is a specification, reference being had to the accompanying drawing for an exemplification of my design.

Referring to the drawing, A is a base plate having a portion A' wider than the rest of the plate. Side walls are formed around the base plate, C, C indicating the walls opposite the broader part A' of the base, D, D showing the walls opposite the narrow part of the plate, and H indicating the wall at the end of the chute.

G and F, F, indicate openings in the broad part A' of the base plate.

As indicated at E, E, the corners are rounded off opposite the broader portion A' of the plate A.

I indicates a tapering aperture in the base-plate A.

What I claim is—

The design for an insulating chute substantially as shown and described.

In witness whereof I have hereunto set my hand this 17th day of November, 1894.

WILLIAM B. POTTER.

Witnesses:

B. B. HULL,
A. F. MACDONALD.
